UNITED STATES PATENT OFFICE.

JOSEPH R. JARNAGIN, OF CHATTANOOGA, TENNESSEE.

DESIGN FOR A BALE-OF-COTTON TOY ANIMAL.

46,854.

Specification for Design.

Patented Jan. 12, 1915.

Application filed October 29, 1914. Serial No. 869,319. Term of patent 3½ years.

To all whom it may concern:

Be it known that I, JOSEPH R. JARNAGIN, a citizen of the United States, residing at Chattanooga, in the county of Hamilton and State of Tennessee, have invented a new, original, and ornamental Design for a Bale-of-Cotton Toy Animal, of which the following is a specification, reference being had to the accompanying drawing, forming part thereof.

The figure is a side elevational view of a bale of cotton toy animal, showing my new design.

I claim:—

The ornamental design for a bale of cotton toy animal, as shown.

JOSEPH R. JARNAGIN.

Witnesses:

RUSSELL K. ANNIS,
FRED. J. HOWARD.
